UNITED STATES PATENT OFFICE.

WILLIAM AIKEN TAYLOR, OF WINNIPEG, MANITOBA, CANADA.

FILM-DRYING APPLIANCE.

1,407,961.

Specification of Letters Patent. Patented Feb. 28, 1922.

Application filed July 19, 1920. Serial No. 397,499.

To all whom it may concern:

Be it known that I, WILLIAM AIKEN TAYLOR, of the city of Winnipeg, in the Province of Manitoba, Canada, have invented certain new and useful Improvements in Film-Drying Appliances, of which the following is a specification.

The invention relates to film drying appliances and the general object of the invention is to provide a machine by the use of which a considerable quantity of films can be quickly and safely dried and to arrange the appliance so that the films can be easily and quickly inserted or removed.

A further object is to construct the machine in a simple, light and compact manner and such that it is unnecessary to employ artificial heat or an air blast to effect the drying.

A further object is to arrange the machine so that the individual films are in tension when the machine is in use and such that they can be quickly set or removed when loading or unloading the machine.

A further object is to arrange the machine so that it will be balanced when the films are inserted.

With the above more important objects in view the invention consists essentially in the arrangement and construction of parts hereinafter more particularly described and later pointed out in the appended claims, reference being had to the accompanying drawings in which:

Fig. 1 is a side view of the complete machine.

Fig. 2 is a plan view thereof, one side being filled with films and the other side open.

Fig. 3 is a front view of the machine.

Fig. 4 is a vertical sectional view through a part of the machine.

Fig. 5 is an enlarged detailed side view of one of the roll holders and attached clip.

Fig. 6 is an edge view of the parts appearing in Fig. 5.

Fig. 7 is a perspective view of one of the film tension wires.

Fig. 8 is a perspective view of one of the locking bolts.

Fig. 9 is a perspective view of a modified arrangement for holding the films.

In the drawings like characters of reference indicate corresponding parts in the several figures.

The present practice in drying films is to fasten the films at the top and bottom in an extended fixed position and then apply arti-

ficial heat for drying them or subject them to a hot blast from an electric fan or such like. This operation takes a considerable time to complete the drying.

According to my invention I provide a machine presenting a rotary film carrying structure in which the films are suspended under tension and which by virtue of its rotation through the air effects the quick, safe and proper drying of the films and without necessitating the use of heated air or a blast.

In this connection I might mention that with my machine I can dry the films in considerably less than half the time which it takes under the older methods and there is positively no possibility of damaging the films.

Referring now to the drawings: 1 and 2 represent a pair of opposing standards suitably bolted to the floor and provided at their upper ends with bearings 3 and 4 which receive rotatably a cross shaft 5 suitably held against end movement.

Adjoining one of the standards I locate a similar standard 6 presenting a bearing 7. The standard 1 is supplied with a cross bar 8 which provides a bearing 9. The bearings 7 and 9 carry rotatably a countershaft 10 fitted between the bearings in the present instance with three different sized driving pulleys 11, 12 and 13. The shaft 5 is also supplied with three different sized driving pulleys 14, 15 and 16. These pulleys allow of a varying speed drive between the shafts 10 and 5. In the present structure the central pulleys 12 and 15 are shown as connected by a belt 17.

18 is an electric motor of any approved type the driving shaft of which is fitted with a pulley 19 connected by means of a belt 20 to a pulley 21 secured to the shaft 10. Obviously the motor when running will effect the turning of the shaft 5 at any of the three speeds provided, depending on the setting of the belt 17.

The shaft 5 carries between the standards 1 and 2 a rotary film supporting structure which is in reality an open frame work in which the films to be dried are mounted. The supporting structure is now described in detail.

22 and 23 are a pair of opposing normally upright side bars permanently secured centrally of their length to the shaft and they are connected at their upper and lower ends by connecting bars 24 and 25, the connecting bars and side bars forming an open centered rectangular frame.

To the upper and lower ends of the bars 22 and 23 I secure permanently upper and lower pairs of equal length cross bars 26 and 27, 28 and 29 which are positioned at right angles to the bars 22 and 23 and are secured permanently midway of their length to said bars. The cross bars form supports for rectangular open centered gate or door like wire carrying frames 30 which are hinged 10 at the top and bottom at 31 and 32 to the cross bars.

Here it will be observed that there is an equal number of these wire carrying frames at each side of the central shaft 5 so that the 15 structure is balanced on the shaft.

In the present instance I have shown two of the wire carrying frames at each side of the shaft and in referring to Fig. 3 it will be observed that the inner gate in each instance is hinged to the cross bars 27 and 28 whilst the outer gate in each instance is hinged to the cross bars 26 and 28. By this arrangement it is possible to open the gates to the position shown at the left hand side of 25 Fig. 2, such permitting of the easy insertion of the film racks as later described.

The gate like frames are normally held closed by locking bolts 33 located at the upper free corners of the gates and designed 30 to engage with retaining straps 24 secured to the cross bars.

Each gate like frame is supplied with a plurality of spaced taut wires 35 which run from the top to the bottom of the frame and 35 these wires each carry a tension wire 36 which has one end formed into an eye 37 slidably mounted on the wire 35 and the other end formed into a hook 38. The arrangement of these tension wires is such that 40 they will lock themselves against movement on the wires 35, this being by way of a rocking and biting action of the eye on the wire 35 in the up swinging of the hooked ends 38. The connecting bars 24 and 25 are also fitted 45 with spaced vertically disposed taut wires 39 similar to those designated 35 and also fitted with tension wires 36.

The upper and lower pairs of cross bars 26 and 27, 28 and 29 are fitted with opposing 50 pairs of notches 40 which are adapted to receive removable film racks 41 which pass across between the bars and have their ends received within the notches.

These racks are in the nature of square 55 sticks and the ends of the sticks are prevented from rotating by making a neat fit in the notches. On the racks I mount a plurality of roll holders 42, these being provided with square central openings 43 to receive the racks and each carrying a spring clip 44 at its lower end. The roll holders 60 are also supplied with riders 45 and 46 which ride the top sides of the racks and also serve to space and interlock the adjacent holders.

65 I have not considered it necessary to enter

into the details of these holders as they are a commercial commodity now on the market and well known to those familiar with the art.

The holders are adapted to support the films from the racks, each holder carrying 70 a film, the upper end of the film being caught by the spring clip 44 in each instance. The interlocking riders 45 and 46 serve to prevent the holders from tilting and they also positively space the holders, thereby keeping 75 the films a fixed distance apart.

To the lower end of each film, which is indicated generally by the reference numeral 47, I attach a second spring clip 48 identical to that 44 and here it will be observed that 80 the lower or bottom spring clips are supplied with a cross opening 49 adapted to be caught on the hook 38.

In actual practice the racks are filled with 85 films to their capacity and are then inserted in the machine, the gate like wire frame being previously opened. There is a wire 85 (39) in the machine for each film and the wires are spaced so that when the films are inserted the wires are directly opposite the 90 films.

After each rack of films is inserted the tension wires 36 are hooked into the openings of the clips 48 and then the attendant pushes down the eye end of the tension wires 95 until the films are pulled tight. The tension wires lock themselves on the wires 35 (39) the eyes biting on these wires.

Here I wish it to be noticed that the pairs of notches 40 are in say the right hand ends 100 of the bars 26 and 27 and in say the left hand ends of the bars 28 and 29. By arranging, the notches in this way one can fill the rotary frame structure by first putting a rack in one side, then turning 105 the frame structure and putting the second rack in the other side, this operation of filling at opposite sides being repeated until all the racks are inserted. After the inner racks have been inserted and 110 the films drawn taut the inner gate like wire frames are closed one after the other and locked, then the other racks are inserted and the outer gates are closed and locked.

When the machine is filled the motor is 115 started and the frame structure rotates at whatever speed is selected and the films are quickly and effectively dried by the air through which they are passed. This way of drying films by rotating them in a rotary frame structure is a particularly quick one and I have found from actual experience that I can dry the films in considerably less than half the time it takes to dry them under older methods where hot air or an air blast 120 is used on stationarily suspended films.

The arrangement of the present machine is particularly convenient as very little time is lost in filling or emptying the machine and obviously the capacity of the machine is such 125 130

that a considerable quantity of films can be dried in one operation.

The roll holders herein shown are more or less of a late introduction in the trade and in establishments where they are not at present used the practice is to suspend the films on wire rods, the upper ends of the films being carried by spring clips slidably mounted on the rods.

10 In order to accommodate the wire rods I have provided pairs of blocks 50 on the cross bars 26 and 28 and 29 and adjoining the slots (see Fig. 9), the blocks being supplied with small slots adapted to receive the ends 15 of the wire rods 51. The spring clips on the rods are indicated at 52.

Whilst I have entered into a detailed description of the rotary frame structure it will be readily understood that I do not wish 20 to be limited to the precise details shown as these could be readily modified without in the least departing from the spirit of the invention as set forth in the accompanying claims.

25 What I claim as my invention is:—

1. A film drying machine comprising a rotatable carrier provided with film securing means engageable with opposite ends of the film strips to hold the latter taut during rotation of the carrier.

2. A film drying machine comprising a rotatable carrier, movable gates supported by the carrier and co-operating film securing means carried by said gates and carrier.

35 3. A film drying machine comprising a rotatable carrier, gate frames hinged to said carrier and securing means on the carrier and gate frames arranged to hold the film strips taut during rotation of the carrier.

40 4. A film drying machine comprising a rotatable carrier provided with securing devices engageable with opposite ends of the film strips, said securing devices being relatively adjustable to place the film strips under tension.

45 5. In a film drying machine, a rotatably mounted and driven open frame structure, film carrying racks demountably carried by the structure and means for extending and holding the films extended within the structure.

50 6. In a film drying machine, a rotatably mounted and driven open frame structure and film carrying racks demountably carried by the frame structure.

55 7. In a film drying machine, a rotatably mounted and driven open frame structure, racks demountably carried by the structure, means for detachably connecting the upper ends of films to the racks and means carried by the frame structure for catching the lower ends of the inserted films and holding the inserted films under tension.

60 8. In a film drying machine, a rotatably

mounted and driven open frame structure, 65 said frame structure presenting upper and lower pairs of opposing cross bars, film carrying racks demountably carried by the cross bars, said films having each one end free and means carried by the frame structure for 70 catching and holding the free ends of the films and maintaining them under tension whilst in the machine.

9. In a film drying machine, a rotatably mounted and driven open frame structure, 75 said structure presenting upper and lower pairs of opposing spaced cross bars, taut spaced wires carried by the frame structure and positioned in the space between the cross bars, racks demountably carried by the cross 80 bars, film holders mounted on the racks and supporting one end of the films, clips secured to the other ends of the films and tension members detachably connected to the latter clips and having eyes slidably mounted on 85 the wires.

10. In a film drying machine, a rotatably mounted elevated shaft, means for driving the shaft, an open frame structure rotatable with the shaft and presenting upper and 90 lower pairs of spaced cross bars equally spaced from the shaft and positioned at right angles thereto, sets of taut spaced wires extending from the top to the bottom of the frame structure in a location between the 95 cross bars, film carrying racks demountably carried by the cross bars and positioned such that the free ends of the films enter between the sets of wires, clips secured to the free ends of the films and a tension wire mounted 100 on each taut wire and having an eye slidable on the taut wire and a hook engageable with the latter clips.

11. In a film drying machine, a rotatably mounted elevated shaft, means for driving 105 the shaft, an open frame structure rotatable with the shaft and presenting upper and lower pairs of spaced cross bars equally spaced from the shaft and positioned at right angles thereto, open centered gate like 110 frames hinged to the cross bars and adapted to swing outwardly parallel to the cross bars, a set of taut wires carried by each gate and passing from the top of the bottom thereof, a plurality of rack bars demountably carried by the cross bars, film holders slidably mounted on the rack bars and carrying films the free ends of which extend between the gates and tension wires detachably secured to the free ends of the films and operating 115 120 on the taut wires.

Signed at Winnipeg, Man., this 22nd day of June 1920.

WILLIAM AIKEN TAYLOR.
